(57) **CLAIM**

The ornamental design for a fuel cap, as shown and described.

DESCRIPTION

FIG. 1 is a top view of the fuel cap, showing our new design; FIG. 2 is a front elevational view thereof, the rear elevational view being a mirror image thereof;

FIG. 3 is a right side elevational view thereof, the left side elevational view being a mirror image thereof; and, FIG. 4 is a bottom view thereof.

The broken line showing of environment is for illustrative purposes only and forms no part of the claimed design.
